COMBINED POST SUPPORTED LANTERN AND LOUD SPEAKER UNIT

Josef Johann Hammes, Maplewood, Mo., assignor to
Benjamin W. Lowell, St. Louis, Mo.

Application February 5, 1958, Serial No. 49,510

Term of patent 14 years

(Cl. D48—31)

Figure 1 is a view in side elevation of a combined post supported lantern and loud speaker unit showing my new design;

Figure 2 is a view in side elevation thereof rotated 45 degrees from Figure 1; and

Figure 3 is an enlarged view in section of a light globe member taken on the line 3—3 of Figure 2. The loud speaker baffle element as seen from the bottom of the loud speaker is conventional in appearance.

I claim:

The ornamental design for a combined post supported lantern and loud speaker unit, as shown and described.
